COMBINED PIPE CLOSING PLUG AND WRENCH GRIPS

Virgil T. Smith, Hutchinson, Kans.

Application November 9, 1954, Serial No. 33,046

Term of patent 14 years

(Cl. D91—1)

Figure 1 is a perspective view of a combined pipe closing plug and wrench grips showing my new design;

Figure 2 is a bottom plan view thereof;

Figure 3 is a side elevational view; and

Figure 4 is a top plan view.

I claim:

The ornamental design for a combined pipe closing plug and wrench grips, as shown.
